J. OLIPHANT

PUMPING MECHANISM

Filed June 15, 1923

UNITED STATES PATENT OFFICE.

JOHN OLIPHANT, OF CHICAGO, ILLINOIS, ASSIGNOR TO SULLIVAN MACHINERY COMPANY, A CORPORATION OF MASSACHUSETTS.

PUMPING MECHANISM.

Application filed June 15, 1923. Serial No. 645,536.

My invention relates to pumping mechanism.

It has for its object to provide an improved pumping mechanism. A further object of my invention is to provide an improved pumping mechanism adapted to enable the natural flow from a well to be utilized and having improved means for increasing the natural flow by the use of either vacuum or pressure as conditions require. These and other objects and advantages of my invention will, however, hereinafter more fully appear.

In the accompanying drawing I have shown for purposes of illustration one embodiment which my invention may assume in practice.

In this illustrative construction I have shown a pumping mechanism comprising a compressor 1 of any usual construction connected through its discharge pipe 2 to a receiver 3, the receiver in turn being connected through piping 4 with the down-pipe 5 of an air lift pump 6 disposed in the well, and the pump discharging through an up-pipe 7 surrounding the pipe 5, with a proper closed chamber or casing 8.

In my improved construction, means are provided for utilizing the natural flow of the well when conditions permit. Referring more particularly to the casing, it will be observed that the up-pipe 7 is provided with a series of perforations 9 above the bottom of the casing in order to permit the ordinary flow of the well to enter the bottom of the casing 8. Here it will be also noted that a discharge line 10 is provided at the bottom of the casing, the same herein having an outwardly opening check valve 11 of any suitable type disposed therein. Thus it will be observed that with the compressor shut down, the well may operate under its ordinary or natural flow, and that the liquid may flow into the casing 8 and there be caused to develop its own head and flow out through the discharge pipe 10, the valve 11 opening to permit the free flow of the fluid.

Should, however, the ordinary flow of the well not suffice, means are provided for increasing the same by the use of a vacuum in the casing 8. These means herein assume the form of a pipe connection 12 connected between the intake 13 of the compressor and the piping 4 leading to the down-pipe 5 of the air lift pump. As shown, a valve 14 is provided in this pipe connection, while a valve 15 is provided on the atmosphere side of the compressor intake, a valve 16 is provided in the pipe connection 2 to control the communication with the atmosphere, and a valve 17 is provided to control the flow from the receiver. Here, it will also be noted that a check valve 18 of any suitable outwardly opening type is provided on the top of the casing and that an inwardly opening check valve 19 is provided in the down-pipe 5 at a point within and near the top of the casing 8. It will also be noted that an upstanding U-bend 20 of suitable length is provided in the connection to the down-pipe 5 and between the receiver and this pipe, to prevent backflow to the compressor. As a result of this construction, it will be observed that by operating the compressor as a vacuum pump, i. e. closing valves 15 and 17 and opening the valves 14 and 16, the valve 18 will be closed and the valve 19 opened, the air in the casing 8 being exhausted through the valve 19 in such a manner as to create a partial vacuum in the casing and thereby increase the discharge from the well, any drawing of liquid in to the compressor being prevented by the U-bend 20. The liquid discharges through pipe 22 which terminates at or near the bottom of a sump 23, but below the end of the sump discharge pipe 24. This insures that the liquid level in the sump will always be above the end of pipe 22, thus sealing the same so that the vacuum system can be properly started. During the vacuum operation the valve 11 will close automatically and the valve 25 will be opened. Liquid will then be allowed to flow from the well and discharge into the sump from which it is withdrawn through pipe 24 by any suitable means (not shown). It will be seen that the liquid level in the sump will have to be kept lower than the well level so that the vacuum system can operate by itself. Once the system has started the vacuum pump can be shut off and a vacuum held in the casing 8. The vacuum system then works on the siphon principle. It will of course be obvious that the only time when it is necessary to have the level of the liquid in the sump 23 below the well level is when the siphon operation is desired, or, if the sump level is higher than the well level and it is desired to create well

flow by vacuum, it is only necessary to close the valve 25.

It will also be observed that means are provided whereby a positive air lift may be

6 used when desired, an umbrella top 21 on the up-pipe 7 being provided for use in this connection. An air lift is thus readily obtainable when desired by simply closing the valves 14, 25 and 16 and opening the valves 10 15 and 17, whereupon air will be supplied from the compressor to the pipe connection 2 and receiver 3, and from the latter through the pipe connection 4 and bend 20 to the down-pipe 5 of the air lift pump 6. This 15 pump will then in turn mix the air with the liquid in the well in a well-known manner, and cause the resulting mixture to be discharged up through the up-pipe 7 against the umbrella top 21, the air and liquid being 20 separated in the casing, in a well-known manner, and the pressure in the top of the casing being regulated by the valve 18 in such a manner as to cause the liquid in the casing to be maintained under the proper 25 pressure and forced out through the discharge line 10. Obviously, during the operation of the mechanism as an air lift system, the valve 19 will be closed by the pressure of the air, while the valve 11 will be 30 opened by the out flowing liquid.

As a result of my improvement, it will be observed that it is possible for a single installation to be used either in connection with the normal or natural flow of the well, 35 as a vacuum system, or as a positive air lift system, thereby enabling it to deal effectively with diverse conditions of well flow or the like and maintain a desired constant flow into the discharge line. It will also 40 be observed that the mechanism is of a simple character requiring only minor and convenient adjustments, which are readily made, in order to enable it to operate as a system of any of the three types desired.

45 While I have in this application specifically described one embodiment which my invention may assume, it will of course be understood that this form of the same is used for illustrative purposes, and that the 50 invention may be modified and embodied in whole or in part in various other forms without departing from its spirit or the scope of the appended claims.

What I claim as new and desire to secure 55 by Letters Patent is:

1. In a pumping system, natural well flow utilizing mechanism including discharge means, means for utilizing a vacuum to increase the flow, and means automatically operative to close said natural flow discharge when said vacuum means is utilized.

2. In a well pumping mechanism, natural well flow utilizing mechanism, means for utilizing vacuum to increase the flow including discharge means, means for supply-

ing pressure to increase the flow, and discharge means for the liquid from the well separate from said first mentioned discharge means and operative separately therefrom.

3. In a pumping mechanism, natural well flow utilizing mechanism including liquid discharge means, and means permitting selective employment of suction or of pressure to augment directly liquid flow in said discharge means, said means including a common suction and pressure transmitting pipe. 75

4. In a pumping mechanism, vacuum pumping mechanism, and means including a fluid pipe common to said pumping mechanism for substituting pressure at will to effect actual pumping of the fluid to the discharge end. 80

5. In a pumping mechanism having a plurality of discharge means, vacuum pumping mechanism, means for substituting natural well flow utilizing mechanism at will, and means automatically operative to close one of said discharge means when said vacuum mechanism is operative. 85

6. In a pumping mechanism having a plurality of discharge means, vacuum pumping mechanism, means for selectively substituting natural well flow or pressure to meet varying conditions, and means automatically operative to close one of said discharge means when said vacuum mechanism is operative. 90

7. In a pumping system, air lift pumping mechanism, a separator therefor, and means for substituting natural well flow utilizing mechanism at will. 100

8. In a pumping system, air lift pumping mechanism, means for substituting vacuum pumping mechanism at will, and a common supply pipe for said vacuum and air lift pumping mechanisms. 105

9. In a pumping system, air lift pumping mechanism, means for selectively substituting natural well flow or vacuum to meet varying conditions, a natural well flow discharge, and means automatically operative to close said discharge means upon creation of the vacuum. 110

10. In a pumping system, selectively operable natural well flow utilizing mechanism, vacuum operated mechanism, pressure operated pumping mechanism, and a common pipe for controlling fluid pressure for a plurality of said mechanisms. 115

11. In a pumping system, a gaseous fluid pump, natural well flow utilizing mechanism, and means for enabling said pump to supply gaseous pressure to or to produce a vacuum in said mechanism, said means including a fluid connection common to both operations and arranged between said pump and mechanism. 120

12. A pumping system comprising a casing having a natural well flow receiving inlet and a discharge, means for creating a 125

vacuum in said casing, and a second discharge from said casing separate from said first discharge.

18. A pumping system comprising a casing having a natural well flow receiving inlet and a discharge, means for selectively creating a vacuum in said casing or supplying an aerated mixture thereto, and means for automatically closing said discharge upon creation of said vacuum.

14. In combination, an air lift system including a pump, piping connected thereto and having a U-bend therein, a casing having oppositely opening valves therein, and means for selectively creating a vacuum in said casing or supplying pressure to said pump.

15. In combination, a compressor, an air lift system connected to said compressor and including a casing having oppositely opening valves, and valves for selectively connecting said compressor discharge or said compressor inlet to said air lift system.

16. In combination, a compressor, a receiver connected thereto, an air lift system connected to said receiver and compressor and including a casing having a well flow inlet and oppositely opening valves, and valves for selectively connecting said receiver or said compressor inlet to said air lift system.

17. In combination, a compressor, an air lift system connected to said compressor and including a casing having oppositely opening valves, a well-flow inlet in said casing, and valves for selectively connecting said compressor discharge or said compressor inlet to said air lift system.

18. In combination, an air lift system including a pump, a casing having oppositely opening valves therein, a riser pipe with which said pump cooperates connected to said casing, means for selectively creating a vacuum in said casing or supplying pressure to said pump, and means for preventing the

passage of liquid from said casing to said 45 vacuum creating means.

19. A pumping system comprising means whereby natural flow, air lift, or vacuum can be utilized, said means including a common means for receiving and discharging the 50 well flow.

20. A pumping system comprising selectively operable means whereby natural flow, air lift, or vacuum can be utilized, said means including a common means for receiving 55 and discharging the well flow.

21. A pumping system comprising a receptacle, a riser pipe having an opening communicating with said receptacle and adapted to allow the natural flow of the well to freely 60 discharge, an umbrella top disposed over the end of said pipe and within said receptacle, and air lift mechanism adapted to cooperate with said umbrella top.

22. A pumping system comprising a riser 65 pipe, a receptacle disposed adjacent the upper end thereof, means whereby the natural flow of the well may discharge freely from said riser and receptacle, and means for creating a vacuum within said receptacle to 70 aid the well flow.

23. A pumping system comprising a riser 75 pipe and means for increasing the flow therein by subjecting the same to suction or by admitting pressure thereto, said system comprising valve means respectively automatically operative during said different operations.

24. A pumping system comprising a well, a sump, the level of the liquid therein being 80 below the level of the liquid in the well, means for creating a vacuum on said well to permit a flow of fluid into said sump to start a siphon operation, and air lift pumping means for assisting the flow of fluid from 85 said well.

In testimony whereof I affix my signature.
JOHN OLIPHANT.
